UNITED STATES PATENT OFFICE.

RUSSELL P. COOK, OF ST. AUGUSTINE, FLORIDA.

RAIL-TIE AND RAIL-JOINT COMBINED.

No. 812,548.

Specification of Letters Patent.

Patented Feb. 13, 1906.

Application filed November 4, 1905. Serial No. 285,812.

To all whom it may concern:

Be it known that I, RUSSELL P. COOK, a citizen of the United States, residing at St. Augustine, in the county of St. Johns and State of Florida, have invented new and useful Improvements in Railway-Ties and Rail-Joints Combined; and I do declare the following to be a full, clear, and exact description of the invention, reference being had to the accompanying drawings, and to the letters of reference marked thereon, which form a part of this specification.

This invention relates to ties or sleepers for supporting railway-rails on road-beds, and the invention has particular reference to composite ties that are constructed of metal and concrete and to ties that are adapted with the rail-fastenings thereof to form a rail-joints.

Objects of the invention are to provide a composite railway-tie that may be produced at the minimum cost and also be adapted to be handled economically prior to being placed in position for use, to provide a composite tie that may be used and have ballast tamped under it in substantially the same manner as wooden ties are used and kept in alignment, to provide rail-fastenings for the tie that may serve as rail-braces, and to provide rail-fastenings and splice-bars combined.

With the above-mentioned and minor objects in view the invention consists in a composite railway-tie of novel construction, in novel combined rail fastenings and braces, and in novel combined rail-fastenings and splice-bars; and the invention consists, further, in the parts and combinations and arrangements of parts, as hereinafter particularly described and claimed.

Referring to the drawings, Figure 1 is a perspective view of a railway-tie and combined rail - fastenings and splice-bars constructed in accordance with the invention and fragments of rails in connection therewith; Fig. 2, a transverse sectional view of a rail and fastenings and longitudinal vertical sectional view of an end portion of the tie taken centrally thereof; Fig. 3, an end elevation of the metallic portion of the tie without the rail-fastenings thereof; Fig. 4, a longitudinal vertical central sectional view of the tie without the fastenings; Fig. 5, a perspective view of one of the combined rail-fastenings and splice-bars; Fig. 6, a perspective view of one of the plain forms of rail-fastenings of

the tie; and Fig. 7, a transverse sectional view of the tie without the fastenings thereof, taken near an end of the tie.

Similar reference characters in the several figures of the drawings designate corresponding elements or features of construction or arrangement thereof.

In a practical embodiment of the invention an essential main part of the tie is composed of iron or steel, and it comprises two end portions A and A' and a middle portion B, all formed integral and having a shell-like form, there being a top and two sides thereof, and the main part may be formed suitably of channel-section iron or steel pressed to the desired shape in dies by a powerful press, or the part may be cast of steel in a mold. The middle portion B is preferably narrower than the end portions A and A', and parts of the tops of the end portions are elevated or pressed up and form rail-chairs C and C'—one near either end of the tie—somewhat higher than the remaining portions of the tie. Each chair is provided at the outer edge of the top thereof with two gage-ears D and D', that are inclined above the top of the chair, and the ears may be punched out of the metal of the chair. The width of the top of each chair is equal to the width of the base of a rail that is to be used. A suitable number of stay-rods a, b, c, d, and e are attached to the sides of the main part of the tie and extend horizontally from one to the other side thereof. The sides of the chairs have bolt-holes f and f' therein, that are arranged in alignment longitudinally of the tie immediately below the tops of the chairs.

The rail - fasteners, which are essential parts of the ties, comprise a brace form of clip that consists of a body part E, that is adapted to be placed against a side of a chair, the body part having a bolt-hole g to receive a bolt that may be inserted in the holes f and f'. The body part E has heels h and h', that are adapted to bear upon the top of the tie, and an oblique-angled flange F to engage the top of a rail-flange, and a brace G to bear against the outer side of the rail-web and the under side of the rail-head. This form of clip is to be used at the outer sides of the rails and, if desired, may also be used at the inner sides of the rails. Another form of fastener comprises a plain clip for use at the inner sides of the rails and consists of a body

part E^2 , having heels h and h' and flange F^2 , all identically like the corresponding parts of the first-described clip, the body part having the bolt-hole g therein.

5 The combined fastening and splice-bar for use where rail-joints occur upon a tie consists of a body part E' , having the hole g and the heels h and h' and flange F' , all formed as above described, and a splice-bar G' is attached to the flange F' and is provided with bolt-holes i to receive joint-bolts j for securing the splice-bars to the sides of rails at the joint ends thereof.

A bolt H and nut are provided for each rail-chair and set of rail-fastenings and are adapted to extend through the holes f and f' of the chair and through the holes g of a pair of clips and to secure the clips to the chair and also to a rail, as k , or to two rails, as l and m , 20 at a joint n .

The body I of the tie is composed of concrete, that is filled into the main metallic part while the latter is inverted, and the concrete is in the form of plastic material, the plastic 25 material surrounding the stay-rods and filling the interior of the rail-chairs, so that the chairs form substantial foundations for the rails. The concrete body preferably is formed on or near the ground where the tie is 30 to be used.

In practical use the ties are to be placed upon ballast, and ballast will be filled in between the ties, as usual, and tamped under them to level them to grade. The rails 35 should be arranged so that joints will occur on ties, so that the chairs may form parts of the joint-supports in connection with the splice-bars that are combined with the rail-fastening clips. Having laid the rails upon 40 the chairs, the outer flanges of the rails are to be pushed under the gage-ears, which will insure correct gaging of the rails. Then the clips and the splice-bars are to be secured by their bolts, as above mentioned.

45 Having thus described the invention, what is claimed as new is—

1. A composite railway-tie including a metallic main part comprising sides and a top and provided with elevated hollow rail-chairs having bolt-holes therein, a concrete 50 body in the main part extending into the hollow rail-chairs, bolts fitting in the bolt-holes,

and pairs of clips having bolt-holes therein to receive the bolts.

2. A composite railway-tie including a metallic main part comprising sides and a top and provided with elevated hollow rail-chairs having bolt-holes therein, a plurality of stay-rods extending from side to side of the main part and secured thereto, a concrete body in the main part extending about the stay-rods and into the hollow chairs, bolts fitting in the bolt-holes, and pairs of clips having bolt-holes therein to receive the bolts. 65

3: A railway-tie and rail-joint combined comprising a metallic main part provided with elevated rail-chairs for supporting abutting rail ends and having horizontal bolt-holes therein, rail-fastening clips for holding 70 the rail ends on the chairs and provided with perforated splice-bars for holding the rail ends together, the clips having bolt-holes therein, bolts fitting in the bolt-holes of the chairs and the clips, and a concrete body in 75 the main part and extending into the rail-chairs.

4. A railway-tie including a metallic main part provided with elevated hollow rail-chairs having gage-ears at the tops thereof, a concrete body in the main part extending into the rail-chairs, clips for holding rails on 80 the chairs, and bolts for securing the clips to the sides of the chairs.

5. A composite railway-tie including a metallic main part comprising a top provided with integral gage-ears and sides attached to the top, a concrete body in the main part, and pairs of rail-clips attachable to the top 85 of the main part. 90

6. A railway-tie and rail-joint combined comprising a main part having bolt-holes therein, rail-fastening clips for holding the rail ends on the main part and provided with perforated splice-bars for holding the 95 rail ends together, the clips having bolt-holes therein, and bolts fitting in the bolt-holes of the main part and the clips.

In testimony whereof I affix my signature in presence of two witnesses.

RUSSELL P. COOK.
